UNITED STATES PATENT OFFICE.

JEREMIAH E. MATHEWSON, OF BROADHEATH, ENGLAND, ASSIGNOR TO BENJAMIN C. TILGHMAN, JR., AND RICHARD TILGHMAN, OF PHILADELPHIA, PENNSYLVANIA.

APPARATUS FOR DRYING MOLDS.

No. 903,391.

Specification of Letters Patent.

Patented Nov. 10, 1908.

Application filed March 1, 1906. Serial No. 303,596.

To all whom it may concern:

Be it known that I, JEREMIAH EUGENE MATHEWSON, a subject of the King of Great Britain and Ireland, residing in Broadheath, in the county of Chester, in the Kingdom of Great Britain, have invented a certain new and useful Improvement in Apparatus for Drying Molds, (for which I have obtained British Letters Patent No. 4,656 of 6th March, 1905,) and of which the following is a true and exact description, reference being had to the accompanying drawings, which form a part thereof.

My invention relates to the drying of molds and has for its object to provide suitable apparatus for passing air downwardly through a fire and if necessary to cool down or reduce the temperature of the hot gases so produced before they enter the mold.

With this object in view my invention consists in the details of construction and manner of operation set forth in the following description and accompanying drawing in which like reference characters refer to corresponding parts.

In the drawing, A, is the body portion of a cylindrical casing or outer shell supported upon the flat ring P by the legs B, B. The removable lid or top J, is hinged at f', to the upper end of the casing and has an opening in the center thereof. Projecting upward from this opening is a conduit K, which is turned into an elbow open to the atmosphere. Projecting downwardly through the top of this elbow is the nozzle L, the said nozzle being connected up to a suitable apparatus (not shown) for storing or generating compressed air. Within the casing opposite the opening in the lid or plate is a baffle plate M, supported by arms fastened to the interior of the casing. Below said baffle plate is a fire box comprising a cylindrical metallic shell f, which shell contains a magazine F, composed of ganister, fire brick, or other refractory material. Below this magazine is supported a hearth G, leaving an annular space between the lower end of the wall of the magazine, and the peripheral portion of the upper surface of the hearth. Between the cylindrical shell f, and the casing A, is an annular space over the top of which extends the outwardly turned annular perforated flange H. Attached to the flange H, between any two of its perforations is a lug a, into which is

screwed the handle i. This handle extends 55 through a horizontal slot in the casing, and attached to the said handle is a plate b, overlapping the edges of the slot on the interior of the casing for the purpose of keeping the slot closed when the handle is moved. The 60 annular perforated flange H of the shell rests upon another perforated annular flange N. The flange N, is bolted to the casing A, and supports the magazine F, together with its metallic shell f, by means of the outwardly 65 turned flange H of the latter; thus forming a register which may be opened or closed to the passage of air therethrough. Around the annular opening between the lower edge of the magazine wall and the outward periphery of the hearth, is a cylindrical ring Q. The said ring extends above and below the said opening, and is supported by the arms e, e, connecting the hearth G with casing A. The said ring is held in a position about midway between the shell of the magazine and the outer casing by the radial pins g, g.

From an outlet in the bottom of the casing projects the pipe R which enters a flanged tube E, placed over the opening into the 80 mold. The said pipe is shown projecting upwardly into the bottom of the casing A, thus forming a wall around the outlet to prevent ashes that may have accumulated in the bottom of the casing from passing through 85 the outlet. It is not necessary, however, that the said wall should be formed by projecting the pipe R into the casing, as the said wall may be formed separately from said pipe and arranged around the outlet in 90 any other manner, provided it prevents the ashes from entering the outlet. The arrangement of this tube or wall around the outlet, or so that the outlet will be within it, forms, together with the outer casing A, an 95 ash chamber at the lower end of the casing. The entire apparatus including the flanged tube E, may be moved from one mold to another by the handles C, C, thus it has all the advantages of a portable structure. A door 100 D is attached to the lower part of the casing which may be opened to obtain access to the lower end thereof when it is necessary to remove the ashes.

By turning on the cock O, in the compressed air connection the said air issues in the form of a jet through the nozzle L, into the conduit K, thus forming, together with

said conduit, an injector for the drawing in of air at the opening in the elbow. The air is prevented from blowing directly into the magazine F, by the baffle plate M, which 5 fuses the same so that part of the air passes downwardly through the fire in the magazine F, and on the hearth G, while the other part of the air passes through the perforated rings H and N, the two streams entering together 10 from the annular space into the chamber below where they have time to mix completely before use. The hot gases are thus toned down to the temperature required for drying purposes. The temperature of the mixture 15 may be regulated by varying the proportion of the volume of air permitted to pass through the register opening around the top of the annular space, which may be entirely closed if necessary. The baffle plate M above the fire box effects a more perfect distribution of air before its division into the relatively hot and cold streams when the register H is open, and the cylindrical baffle ring Q directs the production of combustion 20 into the chamber below the hearth. Fuel may be introduced into the magazine F, at 25 the top thereof by opening the top of lid J.

The herein described apparatus is characterized, among other things, by the passing 30 of the air downwardly through the fire by virtue of which I obtain a heated element free from carbon and smoke because any carbon and smoke from the fresh fuel on the top of the fire are consumed in passing through 35 the same. There is therefore nothing to deposit in the molds or cause obstruction in any way and the whole operation of drying is much cleaner and more satisfactory than heretofore.

40 In the ordinary apparatus for drying molds in which the blowing is upwards through the fire this operation is bound to carry off more or less quantities of carbon and smoke. These products, due to the 45 pressure of air, create combustion and burn in the pipe leading to the mold. The regulation of the temperature of the heated drying element being impossible under these conditions the operation results in causing 50 injury to the mold unless great care is used.

The need for a large connecting pipe from a blower is obviated in the present apparatus because the quantity of compressed air necessary to produce the blast is comparatively small and thus can be delivered to the apparatus by a light flexible tube of small diameter and of any length. The connection of this tube with the apparatus may be made by means of any simple appliance with 60 great facility and at the upper part, where it will be out of the way of the workmen. My apparatus will thus be available for use over a much larger area than the ordinary apparatus besides being much simpler in construction, much lighter and easier to operate. 65

While the device above described is portable, economical and efficient in its operation, I do not wish to confine myself to the exact details thereof as the same may be materially modified and only illustrates one form of carrying out my invention.

Having now described my invention what I desire to claim and secure by Letters Patent is

1. An apparatus for drying molds consisting of a fire containing chamber, means for passing air downwardly through said chamber and means for directing the gaseous products of combustion into a mold. 75

2. An apparatus for drying molds, consisting of a fire containing chamber, means for passing air downwardly through said chamber, means for admixing other air with the hot gaseous products of combustion and means for directing the resulting mixture 80 into a mold. 85

3. In an apparatus for drying molds the combination with a portable casing, of a fire containing chamber within said casing so arranged as to leave an air passage between 90 said casing and chamber, means for passing air downwardly through said chamber and through said passage, an admixing chamber for receiving both the gaseous products of combustion from the first mentioned chamber and the air from the passage, and a conduit for directing the resulting mixture into a 95 mold.

4. In an apparatus for drying molds, a casing, a fire containing chamber within said casing through which air may be passed in a downwardly direction, the said casing having an air inlet at its upper end and an air outlet at its lower end, means for passing air through said casing both through and around 100 said fire box and means for regulating the volume of air passing around said fire box. 105

5. In an apparatus for drying molds a casing having an air inlet at its upper end and an air outlet at its lower end, a fire box located 110 within said casing, means for passing air downwardly through said casing both through and around said fire box and a baffle plate interposed between the opening in the upper end of the casing and the upper end of 115 the fire box.

6. In an apparatus for drying molds, a casing having an open ended conduit projecting from its upper end, an air outlet at its lower end, a fire box through which air may be 120 passed within said casing, an outside passage for air between said fire box and the interior of said casing, a baffle plate interposed between the mouth of said conduit and the fire box, a compressed air nozzle directed downwardly near the open end of said conduit and means for varying the area of the entrance of 125 said outside passage.

7. In an apparatus for drying molds, a casing having an air inlet at its upper end and an 130

air outlet at its lower end, a fire box located within said casing and having a lateral opening around its lower end, a baffle plate interposed between said opening and the said casing and means for passing air downwardly through said casing, both through and around said fire box.

8. In an apparatus for drying molds, a casing having an air inlet at its upper end and an air outlet at its lower end, an inwardly projecting wall surrounding the outlet to form in the bottom of the casing an annular ash chamber, a fire box located within the casing and means for passing air downwardly

through said casing, both through and around said fire box.

9. An apparatus for drying molds, comprising a portable casing, a top fed, solid fuel furnace contained therein, means for passing air into said casing above said furnace, and a conduit leading from beneath the furnace for directing the products of combustion into the mold to be dried.

JEREMIAH E. MATHEWSON.
